UNITED STATES PATENT OFFICE.

GEORGE W. NEWTON, OF HUBBARD, OHIO.

CAR-WHEEL-FLANGE LUBRICATOR.

SPECIFICATION forming part of Letters Patent No. 710,709, dated October 7, 1902.

Application filed May 23, 1902. Serial No. 108,694. (No model.)

To all whom it may concern:

Be it known that I, GEORGE W. NEWTON, a citizen of the United States, residing at Hubbard, in the county of Trumbull and State of 5 Ohio, have invented a new and useful Car-Wheel-Flange Lubricator, of which the following is a specification.

This invention relates to devices employed for the purpose of lubricating the flanges of 10 car-wheels, more particularly of the wheels of street-cars, when passing around curves at the points where the wheels bear against the guard-rails and also when passing other points where excessive wear occurs, as at frogs and 15 switches.

The invention consists in certain novel features of the construction, as hereinafter shown and described, and specified in the claims.

In the drawings illustrative of the invention, Figure 1 is a longitudinal sectional elevation. Fig. 2 is a transverse sectional elevation. Fig. 3 is a bottom plan view.

The device may be applied to any form of railway or street car, either steam, electric, 25 or other style; but for the purpose of illustration it is shown applied to an ordinary street-car truck, 10 representing the platform, 11 11^a the axles, and 12 12^a 12^b 12^c the flanged wheels, each having its respective flange 13 30 of the ordinary construction. The truck, axles, and wheels and their connections are of the usual construction, as the invention is applicable to any of the various forms of street-car structures. The rails are represented at 13^a, each with its respective guard-rail 14 14^a, usually formed in one piece with the rail, as shown, in street-car construction. In ordinary railway construction the guard-rails are formed of ordinary rails spaced from 35 40 the main rails and suitably braced, and the invention is applicable to that particular form or any other form of guard-rail usually employed.

The device which is the subject of the present invention is designed to apply a lubricant to the flanges 13 instead of to the inner face of the guard-rail, as in ordinary railway construction, and this lubricant-applying means consists of rollers 15 15^a 15^b 15^c, preferably 50 one for each wheel, as shown. These rollers are formed of some soft or yieldable substance which will absorb the lubricant and impart

it to the flanges 13 when engaged therewith, from which it will be transferred to the guard-rails as the wheels revolve, and thus lubricate the guard-rails and minimize the friction caused by the "slip" of the inner wheels in passing around curves. In the ordinary street-car construction the lubricant, generally in the form of a semisolid, is applied by 55 hand to the guard-rail; but this is a laborious and wasteful process, as it is almost impossible to apply the lubricant in the place most required. With the improvement herein illustrated, however, the lubricant can be applied 60 to the exact spot required and no more of the material used than may be necessary and used only when necessary, so that the tracks will not be unduly coated with the lubricant material, as is the case when applied by hand 65 in the ordinary manner. The rollers will be arranged to apply the lubricant only at such times and places as it may be required and will remain out of engagement with the flange-wheels when not required, so that the lubricant 70 will be employed with the greatest economy and undue coating of the wheels and tracks avoided. Some means will be employed under the control of the conductor, engineer, or motorman whereby the rollers may 75 be engaged with the flanges when required, and an approved means for thus operating the rollers is illustrated in the drawings. The rollers are mounted upon the opposite ends of shafts 16 16^a, respectively, each shaft supported 80 from the platform 10 by hangers 17, the shafts adapted to be rotated in the hangers to cause the rollers to be engaged with and disengaged from the flanges on the traction-wheels or to be supported out of engagement 85 with the flanges at the will of the operator. An approved form of mechanism for rotating the shafts 16 16^a consists in a longitudinal shaft 18, centrally supported beneath the frame 10 by hangers 19 and with one end extending upward through the platform convenient to the hand of the motorman, as indicated at 20, and supplied with a spring 21, by which the shaft and its operating-arm 20 will be maintained 90 normally in their central positions. Rising from the shaft 18 is an arm 22, connected by oppositely-extended rods 23 23^a, and two arms 24 24^a, respectively extending from the shafts 16 16^a, by which means, it will be readily un-

derstood, the rotation or oscillation of the shaft 18 by its arm 20 will cause the shafts 16 16^a to be correspondingly oscillated, and thus alternately engage the rollers 15 15^a and 15^b 15^c 5 with the flanges of the traction-wheels. By setting the arm 20 vertically in the car-frame, it will be noted, the lubricating-rollers will be supported out of engagement with the flanges of the traction-wheel, and when the 10 arm 20 is moved to the right or left the lubricating-rollers will be correspondingly engaged with the opposite flanges, and thus impart thereto the requisite lubrication, as before noted. By this simple arrangement the 15 absorbent rollers, being charged with a suitable lubricating material, may be engaged with the flanges of the traction-wheels at any desired point in the line of the road and to either side of the track, as the case may be, 20 to properly lubricate the guard-rails, as above noted.

Any suitable material may be employed as a covering for the lubricating-rollers, such as sheep-pelt, saturated with oil or grease and 25 large enough to engage a sufficient space upon the flange to lubricate all the parts which may engage the guard-rail. The lubricating-rollers may be of any size required and may be of any suitable length and will preferably 30 be concaved to engage the curved inner face of the flange.

The shafts 16, 16^a, and 18 may be of any size and suspended from the framework in any suitable manner and will be modified to 35 conform to the trucks of the various constructions employed.

Any suitable form of the holding-spring 21 may be employed to maintain the handle 20 in its normally central position.

40 The various parts may be altered and modified in minor particulars without departing from the principle of the invention or sacrificing any of its advantages.

The lubricating-rollers may be arranged to 45 be applied to any required part of the wheel or to any required point of the periphery, according to the construction of the car.

Having thus described my invention, what I claim is—

50 1. A device for lubricating car-wheel flanges, consisting in rollers charged with lubricating material and supported movably adjacent to the flanges, and means for engaging said rollers with said flanges, substantially as described.

55 2. A device for lubricating car-wheel flanges, consisting in rollers charged with lubricating material and supported movably adjacent to said flanges, a shaft carrying said 60 rollers, and means for operating said shaft to

cause said rollers to be engaged with said flanges, substantially as described.

3. A device for lubricating car-wheel flanges, consisting in rollers charged with lubricating material and supported movably 65 adjacent to the flanges of the opposite wheels, means for causing said rollers to be alternately engaged with said oppositely-disposed flanges, substantially as described.

4. A device for lubricating car-wheel 70 flanges, consisting in rollers charged with lubricating material and supported movably adjacent to said flanges, means under the control of the operator upon the platform of the car, whereby said rollers are caused to be engaged with said flanges, substantially as de- 75 scribed.

5. In a device for lubricating car-wheel flanges, a supporting-frame, flanged wheels carried by said frame, rollers adapted to be 80 charged with lubricating material, a shaft supporting said rollers adjacent to said flanges and adapted when rotated to cause said rollers to engage said flanges, and means for rotating said shaft, substantially as de- 85 scribed.

6. In a device for lubricating car-wheel flanges, the truck-frame, flanged wheels supported upon axles carried by said truck-frame, rollers adapted to be charged with lubricat- 90 ing material, shafts supporting said rollers adjacent to said flanges and adapted, when rotated to cause said rollers to engage said flanges, a longitudinal shaft connected to said roller-shafts and adapted to alternately 95 oscillate them, and means for operating said longitudinal shaft, whereby said rollers may be alternately engaged with the opposite wheels upon said axle, substantially as de- 100 scribed.

7. In a device for lubricating car-wheel flanges, the truck-frame, flanged wheels supported upon axles carried by said truck-frame, rollers adapted to be charged with lubricating material, shafts supported from said truck-frame and carrying said rollers, a longitudinal shaft supported from said truck-frame, means for connecting said longitudinal shaft to said roller-shaft, and means for operating said longitudinal shaft, whereby 105 said rollers may be alternately engaged with or disengaged from said flanges, substantially as described.

In testimony that I claim the foregoing as my own I have hereto affixed my signature in 110 the presence of two witnesses.

GEORGE W. NEWTON.
